CLAIM

I claim the ornamental design for a cutting and coagulating surgical jaws, as shown and described.

DESCRIPTION

FIG. 1 is a top perspective view of a cutting and coagulating surgical jaw showing our new design shown in a closed configuration;

FIG. 2 is a bottom perspective view thereof shown in a closed configuration;

FIG. 3 is another top perspective view thereof shown in an open configuration;

FIG. 4 is another bottom perspective view thereof shown in an open configuration;

FIG. 5 is a left side elevational view thereof shown in a closed configuration;

FIG. 6 is a right side elevational view thereof shown in a closed configuration;

FIG. 7 is another left side elevational view thereof shown in an open configuration;

FIG. 8 is another right side elevational view thereof shown in an open configuration;

FIG. 9 is a top down plan view thereof in a closed configuration;

FIG. 10 is a bottom up plan view thereof in a closed configuration;

FIG. 11 is a front elevational view thereof in a closed configuration;

FIG. 12 is a rear elevational view thereof;

FIG. 13 is an enlarged top perspective view showing a portion of the cutting and coagulating surgical tool thereof shown in a closed configuration;

(Continued)

FIG. 14 is an enlarged bottom perspective view showing a portion of the cutting and coagulating surgical tool thereof shown in a closed configuration;

FIG. 15 is an enlarged top perspective view showing a portion of the cutting and coagulating surgical tool thereof shown in an open configuration;

FIG. 16 is an enlarged bottom perspective view showing a portion of the cutting and coagulating surgical tool thereof shown in an open configuration;

FIG. 17 is an enlarged left side elevational view showing a portion of the cutting and coagulating surgical tool thereof shown in a closed configuration;

FIG. 18 is an enlarged right side elevational view showing a portion of the cutting and coagulating surgical tool thereof shown in a closed configuration;

FIG. 19 is an enlarged left side elevational view showing a portion of the cutting and coagulating surgical tool thereof shown in an open configuration;

FIG. 20 is an enlarged right side elevational view showing a portion of the cutting and coagulating surgical tool thereof shown in an open configuration;

FIG. 21 is an enlarged top down plan view showing a portion of the cutting and coagulating surgical tool thereof shown in a closed configuration;

FIG. 22 is an bottom up plan view showing a portion of the cutting and coagulating surgical tool thereof shown in a closed configuration;

FIG. 23 is an enlarged front elevational view showing a portion of the cutting and coagulating surgical tool thereof shown in a closed configuration; and,

FIG. 24 is an enlarged rear elevational view showing a portion of the cutting and coagulating surgical tool thereof shown in a closed configuration.

The broken lines shown in FIGS. 1-24 illustrate portions of the cutting and coagulating surgical jaws that form no part of the claimed design.
